BEAM AMPLIFIER TUBE

Norman Z. Ballantyne, Orofino, Idaho

Application June 16, 1949; Serial No. 99,499

6 Claims. (Cl. 313—72)

1

This invention relates to improvements in electron tubes of the amplifier type.

It is an object of the invention to provide a tube of the beam amplifier type which will enable direct coupling from the anode of a preceding tube to its controlling element and thus provide a direct path for the signal voltage developed across a plate load common to both the controlling element and the anode, without the use of cumbersome biasing and divider circuits as has heretofore been necessary.

A further object of the invention is to provide a tube which can be easily used as a direct current amplifier. Heretofore, in tubes the control element had to be biased below or at the cathode potential requiring cumbersome circuits used without coupling. Such circuits are not necessary with the tube presented herein as one control element is always maintained positive with regard to the cathode, and increasing it positive merely increases the electrostatic lens action; and swinging it negative decreases the lens action.

A further object of the invention is to provide a tube by means of which phase inversion is accomplished. Heretofore, phase inverting circuits required critical adjustment or critical load requirements with little, if any, total gain. With my tube one element under control will alternately increase and decrease the current flowing to each of two electrodes which have equal, opposite changes in current. Phase inversion can be accomplished by the tube itself with the opposite phases removed from the equal plate loads of a target anode and target plate.

A further object of the invention is to provide a tube with a much more linear curve than possible with tubes heretofore produced.

A further object of the invention is to provide a tube with a high internal resistance. In the triode tube, since plate voltage is a direct function of plate current, resistance is extremely low. In the pentode tube a higher resistance is provided due to the action of the screen grid in maintaining almost a constant acceleration potential. But since the plate voltage influences the plate current the tube resistance is not raised too high. (Specifically, in a pentode tube the plate voltage will add to the attraction of the screen grid to increase plate current or subtract from it to decrease plate current.) In my tube, the fact that the plate is completely screened from the cathode will make the tube resistance the vectorial sum of the electron velocity, the electrostatic potential, the electron beam density, the lumped attraction of the target anode and target

2

plate, the point of focus, and the geometrical arrangement of the elements of the tube. Considering all these factors the shift in target plate potential is minor matter, and the resistance will be high.

At further object of the invention is to provide a tube in which there is little change in efficiency as the frequency increases. In tubes heretofore produced, the braking effect of the control grid on the electrons emitted at angles other than the horizontal plane of a vertically aligned cathode causes an appreciable time lag between the time the grid opens and closes and when the electron flow is effected. This transit time between the cathode and the control electrode causes the efficiency to decrease as the operating frequency increases.

At further object of the invention is to provide a tube which will draw a constant current from a power supply. Heretofore, in tubes the current drawn at any particular instant is a function of the voltage applied to the control electrode. In my tube the current drawn from the cathode is constant at all control potentials, and the beam current being constant the power supply load will remain constant under all operating conditions.

At further object of the invention is to provide a tube in which many external circuit parts are eliminated without sacrifice in fidelity of response.

A further object of the invention is to provide a deflection type tube having an extremely high gain. Heretofore, deflection type tubes have not been of high gain because the electrons had to be accelerated off the cathode wall in order to obtain any appreciable electron beam density because the plate or anode must be located beyond the deflection plates. If such accelerating potentials are supplied, the electrons attain such a velocity that the amount of deflection that could be applied by a shift in electrostatic field potential is small. Because of these factors, deflection type tubes have had very low gain. In my tube the formation of an electrostatic lens and thus causing a point of focus to appear, makes possible the deflection of the accelerated electrons by a small change in control potential. A small change in potential changes the contours of the lens and does not cause attraction or repulsion of the electrons in the beam to apply initial electron curves, the control factor of the tube being thus greatly increased. The lens is set up by the formation of an electrostatic potential between the positive and negative deflection plates,

the electron velocity, and the geometrical arrangement of the elements.

To be more detailed, the electrons leaving the accelerating structure near the positive deflection plate are thrown into a curve by the positive potential present and are also accelerated by it. The electrons passing close to the negative deflection plate are repelled from it and attracted both by the positive deflection plate and the lumped attraction of the target anode and target plate. Since the curve of the electrons near the positive plate is near the calculated curve of the positive plate and the curve of these electron paths is flatter than the curve of the electrons near the negative plate, which lose their original linear velocity more readily in approaching the negative deflection plate, the two curves will come together at the point of focus. A shift in potential at one deflection plate causes a shift in the electron curve near that point. Since the various curves are approaching one point with the electrons traveling at relatively the same velocity, that point will have a very high electron density per unit area. Since the electrons contain the same charge, as the density increases as the electrons approach the point of focus the electrons will become mutually repulsive but since their angular velocity is converging the two relative velocities will vector into a resultant component which momentarily, will collimate the electron paths. If the angular velocity component of either of the converging paths is changed, then the resulting vector component will also be changed. By this means the beam will be shifted not so much by the activity of direct electrostatic action but, rather by the change of relative angular velocities of the individual electron paths. It is true that a shift in deflection plate potential does change the electro-static density but it is also true that if both deflection plate voltages were shifted in the same direction at the same time so that electro-static field strength remained constant the beam would still shift.

Thus, in effect a lens is formed between cathode and the target plate and this lens is shifted in contour to control the electron bombardment area. Electro-static action is secondary to the lens action and the two work together.

In the prior art deflection of the beam was accomplished completely by a change in either electro-static or electromagnetic potential. The beam was either diverging or approaching collimation. It was not converging nor was it using vector relationships as a control factor.

Another object of the invention is to provide a tube in which microphonic troubles are, to a large extent, eliminated. In the prior art, a primary cause of microphonics has been the relatively fragile grid windings which may be changed in physical length by an increase in temperature with a resultant loss of rigidity and the possibility of setting up vibrations within the tube structure. It is evident with rigid plates and without grid windings of any kind it is impossible to set up vibrations within the tube due to expansion of the elements of the tube structure. Since all unit lengths are linear to the cathode the major expansion will be parallel to the cathode and, therefore, the rigidity of elements cannot be greatly changed.

Another object of the invention is to provide a tube which does not decelerate the electrons as they leave the cathode wall. This action is a source of inefficient operation in the conventional tube but is eliminated in this invention because

of the constant acceleration applied to the electrons.

Another object of the invention is to provide an electron discharge device in which the electron density per unit area of the beam cross section remains constant or becomes greater. Thus, the problems resulting from a shifting density in the electron stream is eliminated because electron density remains nearly constant.

10 Another object of the invention is to provide a tube which can be constructed of vertically aligned parts. Since these parts expand or contract along the axis of major length with the result that practically zero change can be observed in width, no appreciable change in control constants will result from changes in temperature. This results in constant control factors which are not found in grid type tubes.

Another object of this invention is to provide 20 a tube with the ability to be used as a push-pull amplifier within the one envelope. This is accomplished by controlling the lens action by shifting both negative and positive plate potentials simultaneously but in opposite phases (output can be single end or push-pull).

Another object of this invention is to provide a tube in which there is no phase shift between input and output. Since in the common tube the current through the tube increases with a decrease 30 in negative grid potential resulting in a decrease in plate voltage and consequent reduction in attraction the shift in plate voltage causes a decrease in the actual control exercised by the grid. Also when the grid potential increases (becomes more negative) the plate current decreases with a resulting increase in plate voltage and an increase in plate attraction. This action of the plate voltage opposing the change caused by grid voltage reduces the over-all efficiency of the common tube and results in numerous other problems.

40 In this invention when a control voltage is applied to the negative deflection plate and that plate becomes less negative, the beam is shifted towards the target anode. The target plate therefore becomes more positive and is in phase with the control voltage. A similar relationship exists between the positive deflection plate and the target anode. It is obvious that output voltages in phase with, or out of phase with, the input signal may be taken at will from this tube by using the proper arrangement.

Another object of the invention is the reduction 55 of harmonic distortion. Because of the very narrow limits of the linear curve in the conventional tube and the necessity of biasing and driving the tube within those narrow limits without causing non-linear distortion to appear, circuits must be carefully constructed and operated. An increase in signal voltage slightly above the curve limits causes distortion to appear while a change 60 in circuit components will also cause such distortion.

With an increase in the length of the linear part of the curve, the possibilities of biasing at the wrong point or over driving the tube are consequently decreased. Since only a small part of the curve is not straight so that linear response would result over almost the entire curve harmonic distortion is largely reduced.

70 Still another object of the invention is the reduction of frequency distortion. In the conventional circuit where a cathode resistor is used and by-passed by a capacitor, the capacitive reactance will vary as the operating frequency shifts. Also the common resistive-capacitive

coupling produces changes in capacitive reactance while the operating frequency changes. These points are sources of frequency distortion due to the changing effective A.C. resistance.

In this tube when a resistor is used in the cathode circuit, the voltage drop across that resistor remains constant. Also the fact that direct coupling can be utilized in some circuits, eliminates the need for the coupling capacitor and consequently eliminates this source of distortion if so connected.

It is well to note that other sources of frequency distortion are present, but those sources are not in the province of the tube. Insofar as possible the causes of tube caused frequency distortion are eliminated.

A further object of the invention is to provide a tube which is simple and inexpensive to manufacture. Without the necessity of winding the grids and by constructing completely from easily stamped parts this tube is very inexpensive to manufacture despite the precision required in constructional detail.

Another object of the invention is to provide a deflection type tube of sufficiently small construction to be utilized within the space limitations of the more conventional tubes. Since the overall size of this tube can be less than many of the conventional types it follows that this object has been realized.

These and other objects are attained by the novel construction and arrangement of parts hereinafter described and illustrated by the accompanying drawing, forming a part hereof and in which:

Figure 1 is a plan view of a beam amplifier tube embodying the invention.

Fig. 2 is a sectional view taken on line 2--2 of Fig. 1.

Fig. 3 is a diagrammatic view illustrating an external circuit used in conjunction with the device. Referring to the drawing, the tube is shown to comprise an envelope 1 in which is positioned a cathode 2, which emits electrons from all of its coated surface 3, when properly heated. The coated surface 3 of oxide may completely cover the exterior of the cathode or only a part of it, and the cathode may be round or of a flat construction, or it may have an inwardly curved surface. Whatever the cathode construction may be, the surface coating emits electrons when heated. The emitted electrons are repelled by the neutral or negative charge applied to the focusing structure 4 comprising a cylinder. The opening or gap 5, in the focusing structure provides means for the electrons to pass through the focusing structure towards accelerating structure 6, also comprising a cylinder. The effective width of this gap can be controlled by varying the voltage to the focusing structure. Just beyond the gap the accelerating structure 6 causes the electrons emitted from the cathode wall near the gap to accelerate through the gap towards the accelerating structure, because of the positive potential applied to that structure. As the electrons reach and pass through this structure they have had a high linear velocity applied and the various electron paths are approaching collimation in the vertical plane, considering that the cathode is vertically alined.

In this manner the beam is set up. The focusing structure allows the electrons to move only through the gap causing the formation of a beam in the horizontal plane and the accelerating structure causing the electrons to approach collima-

tions in the vertical plane, with resultant equal electron density along the vertical axis.

Electrons moving outward from the accelerating structure in the region of the positive deflection plate 7, are attracted toward that plate. However, since the electrons have a high linear velocity and the plate bends away from their line of movement they cannot bombard it. The attraction, however, causes some angular velocity to be applied which causes the electron path to become a relatively flat curve.

Electrons moving outward from the accelerating structure 6 in the region near the negative deflection plate 8 cannot bombard that structure although it is directly in their path because it is maintained at or below cathode potential. Since the electrons cannot bombard this structure they begin to lose the linear velocity applied. The potentials to the target plate 9 and the target anode 10 form an attractive field which applies high angular acceleration to the electrons. Thus the electrons follow a sharply curved path between the accelerating structure and the point of focus.

Since the electrons near the positive deflection plate have a relatively flat curve and the electrons near the negative deflection plate have a sharp curve, and the two curves are in the same direction, it follows that the curves will converge as shown in the drawing.

In varying degrees these factors of convergence effect all of the electron paths. With all the electrons approaching one point it is obvious that an extremely high electron density per unit area will develop at the point of focus. The high electron density apparently causes the electron to collimate due to the mutual repulsion at high densities. This causes the beam to become highly concentrated and moving in parallel lines in the horizontal plane.

The electrons approaching the point of focus are traveling at relatively the same velocity, but in different directions. Since the resultant of the several converging paths will be a vector of all the paths, it follows that if one path is changed the final path will also be changed.

Whether the electron beam strikes the target anode or the target plate 9 depends upon the path the electrons near the structure in control (either the positive or negative deflection plate) are caused to take. Increasing the negative potential on the negative deflection plate causes a sharper curve to develop in that region causing the vector resultant of the several curves to move toward bombardment of the target plate 9. Similarly an increase in the positive potential applied to the positive deflection plate will cause a sharper curve near that structure resulting in the beam again moving toward bombardment of the target plate 9. Converse voltage applied would cause the beam to move toward the target anode.

From the above description it will be seen that the electrostatic field shift is only a small part of the total control factor. For that reason this tube is not to be construed as simply an electrostatic deflecting tube. The electrostatic shift is secondary to the lens warp which occurs when deflection of plate potential is applied and shifted.

The separator plate 11 is operated at a lower potential than the target anode insofar as static potential is concerned and will maintain some potential difference even at maximum swings in the voltage applied to either the target anode or target plate. Since it is operated at a lower potential in a field of much higher potential the

total amount of beam current bombarding the separator plate is at no time very large. When the point of focus is placed upon the separator plate the beam will divide on either side of the plate and be flowing equally to the target anode and to the target plate.

From the above description it will be seen that there has been provided a tube using a beam of constant intensity, that is, the current drawn from the cathode is a constant, which is not true in tubes hereofore provided. In addition, in my tube no effort is made to establish electron multiplication or control secondary emission, although such use is not to be disregarded. Furthermore, in my tube the formation of the beam remains constant, its electron density remains constant or increases, the velocity of electron movement, the electrostatic density, and all other operational factors remain constant except for the voltage required to either the positive or negative deflection plates. Control over the beam is exercised by changing the voltage to the deflection plates causing the warping of an electro-static lens.

It will be seen that there has been provided a beam amplifier tube using a beam of constant intensity and near constant density controlled by means of lens warp. The tube draws a current from the cathode which is constant at all times; and shifts in voltage on either the negative or positive deflection plates will produce control action so that either positive control, with the advantage of direct coupling, or negative control, with certain advantages in its favor may be used. If an equal load is placed on the target plate and target anode circuits and the tube is biased properly, power phase inversion from one point of control is realized. Unequal loads may also be used with compensating changes in bias points. In the tube the rise in plate current on either the target plate or target anode becomes linear to the applied signal voltage so that in comparison with ordinary tubes, there is no $E_G - I_p$ curve but, rather, a very near linear rise. This means that harmonic distortion is almost entirely eliminated and that fidelity of response is exceptionally good when the tube is not driven out of its control voltage range. The presence of electro-static fields which cause the electron beam to come to a point of focus, cause the amplification factor of the tube to be high in comparison to other types of beam tubes.

Since the control action and the point of bombardment are very close together and since the amount of current present in the beam remains a constant, the drop off in efficiency as the higher frequencies are applied to the tube will be very small. Relatively small inter-electrode capacity exists between the positive deflection plate and the target plate. Feedback between these two elements, when positive deflection control is used, will, therefore, be relatively low. When negative control is used the fact that the target plate and negative deflection voltage will be in phase will tend to reduce the capacity existing between them.

The tube as presently constructed consists of a single stage amplifier. The foregoing description should in no way limit the application of the same principles to a tube of symmetrical construction of a push-pull type.

The invention having been described, what is claimed is:

1. In an electron discharge device of the beam amplifying type, an envelop, a cathode mounted in the envelop, an oxide coating on the cathode, said coating emitting electrons when the cath-

ode is heated, a focusing structure comprising a cylinder surrounding the cathode, said focusing structure having an opening through which emitted electrons can pass, an accelerating structure beyond the focusing structure and having an opening for the passage of electrons, a positive deflection plate and a negative deflection plate beyond the accelerating structure and curved substantially in the same direction, said negative deflection plate having a curvature greater than the curvature of the positive plate, a target plate curved in the direction opposite to the curvature of the negative plate and arranged to receive electrons from the positive and negative plates, a target anode upon which the electrons are focused, and a separator plate between the target plate and target anode and operated at a lower potential than the target plate and target anode.

2. In an electron discharge device of the beam amplifying type, an envelop, an electron emitting structure mounted in the envelop, a focusing structure comprising a cylinder surrounding the cathode, said focusing structure having an opening through which emitted electrons can pass, an accelerating structure comprising a cylinder having parts thereof mounted beyond the focusing structure and with an opening aligned with the opening in the focusing structure, a positive deflection and a negative deflection plate spaced apart and disposed beyond the accelerating structure and mounted on either side of the gap in that structure with these two members curved substantially in the same direction, said negative deflection plate having an arc length greater than the arc length of the positive deflection plate, a target plate curved in the direction opposite to the curvature of the negative deflection plate and arranged to receive electrons from the beam as directed by the positive and/or negative deflection plates, a target anode arranged to receive such electrons from the beam that are not absorbed by the target plate, and a separator plate between the target anode and the target plate upon which the electrons are focused, said separator plate operated at a lower potential in respect to the cathode than the target plate and target anode.

3. In an electron discharge device comprising an electron emitting cathode, a separator plate, means for focusing the electrons into a beam throughout their path of travel from the cathode to the focus point near the edge of the separator plate, means for accelerating the electrons, a curved positive deflection plate curved in the arc of a circle, and a curved negative deflection plate curved in the arc of a circle, so disposed as to give the beam a substantially curved path, a target anode, a target plate promoting focusing action, and a separator plate which is operated at a potential less positive in respect to the cathode than the target plate and target anode.

4. The structure set forth in claim 1 further characterized by the positive deflecting plate and the negative deflecting plate being curved in the arcs of circles in the same direction.

5. The structure as set forth in claim 1 further characterized by the target plate being curved in the arc of a circle and in a direction opposite to the curvature of the positive deflecting plate, and one end of the separator plate being positioned between and in spaced relation with the target plate and the target anode.

6. In an electron discharge device, a cathode from which electrons are emitted when the cathode is heated, means for focusing the electrons, means for accelerating the electrons, a positive

deflection plate and a negative deflection plate directing the electron beam in a substantially linear path, a target anode, a target plate to assist in focusing the electron beam on the target anode, and a separator plate operated at a potential lower than the target plate and target anode.
